DESIGN FOR A TABLE DESK

Richard W. Ericson, Chicago, Ill.

Application February 28, 1938, Serial No. 75,457

Term of patent 14 years

To all whom it may concern.

Be it known that I, Richard W. Ericson, a citizen of the United States, residing at Chicago, in the county of Cook and State of Illinois, have invented a new, original, and ornamental Design for a Table Desk, of which the following is a specification, reference being had to the accompanying drawing forming part thereof.

Fig. 2 is a perspective rear view of the same.

I claim:

The ornamental design for a table desk substantially as shown.

RICHARD W. ERICSON.
